US00D924007S

(12) **United States Design Patent** (10) **Patent No.:** **US D924,007 S**
(45) **Date of Patent:** **** Jul. 6, 2021**

(54) **STRAINER BLENDER ACCESSORY**

(71) Applicant: **SHARKNINJA OPERATING LLC**,
Needham, MA (US)

(72) Inventors: **Sam William Bannister**, Leybourne
(GB); **Kristof Benedict Fogarasi**,
Norwood, MA (US); **Dan Kestenbaum**,
Brookline, MA (US); **Michael Ting**,
Boston, MA (US)

(73) Assignee: **SHARKNINJA OPERATING LLC**,
Needham, MA (US)

(**) Term: **15 Years**

(21) Appl. No.: **29/694,051**

(22) Filed: **Jun. 6, 2019**

(51) LOC (13) Cl. **31-00**

(52) U.S. Cl.
USPC **D7/412; D7/378**

(58) **Field of Classification Search**

(57) **CLAIM**

The ornamental design for a strainer blender accessory, as shown and described.

DESCRIPTION

FIG. 1 is a perspective view of a strainer blender accessory, showing our new design;

FIG. 2 is a front view of the embodiment shown in FIG. 1;
FIG. 3 is a rear view of the embodiment shown in FIG. 1;
FIG. 4 is a side view of the embodiment shown in FIG. 1;
FIG. 5 is another side view of the embodiment shown in FIG. 1;

FIG. 6 is a top view of the embodiment shown in FIG. 1;
FIG. 7 is a bottom view of the embodiment shown in FIG. 1; and,

FIG. 8 is another perspective view of the embodiment shown in FIG. 1.

The broken lines in the figures are for environmental purposes only and form no part of the claimed design.

1 Claim, 8 Drawing Sheets
